(57) **CLAIM**

The ornamental design for a solar cell module, as shown and described.

DESCRIPTION

The sole FIGURE is a front elevational view of a solar cell module showing our new design.

The broken lines shown represent unclaimed subject matter only. Where broken lines abut a claimed surface it is understood that those broken lines represent an unclaimed boundary between claimed and unclaimed surfaces. None of the broken lines form part of the claimed design.

1 Claim, 1 Drawing Sheet
